The ornamental design for an ice cube release tool, as shown and described.

DESCRIPTION

FIG. 1 is a top perspective view of an ice cube release tool showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a top perspective view of the ice cube release tool in an open configuration of use; and,

FIG. 9 is a top perspective view of the ice cube release tool with the coverings in an exploded state.

The broken lines in the drawings depict portions of the ice cube release tool that form no part of the claimed design.
